UNITED STATES PATENT OFFICE.

MALIN EWING, OF SHARON, PENNSYLVANIA.

POST-OFFICE SEPARATING-CASE.

No. 880,132.

Specification of Letters Patent.

Patented Feb. 25, 1908.

Application filed March 16, 1907. Serial No. 362,749.

To all whom it may concern:

Be it known that I, MALIN EWING, a citizen of the United States, residing at Sharon, in the county of Mercer and State of Pennsylvania, have invented certain new and useful Improvements in Post-Office Separating-Cases, of which the following is a specification.

My invention relates to post-office separating cases, such as are used in distributing a mass of mail matter at a post-office into distinct lots, each of which goes into the hands of a different carrier for further distribution to the addressees.

The object of my invention is to produce improvements in separating cases, whereby the initial distribution of the mail matter to the carriers is greatly facilitated; and my improvements are such as to simplicity and adaptability that they may be with advantage added to the ordinary cases already in use.

To the above and other ends, as will hereinafter appear, the invention consists of the elements, combinations and arrangements of parts, all as will be hereinafter set forth, and succinctly defined in the annexed claims.

Referring to the accompanying drawings, which are to be taken as a part of this specification, and wherein I have shown a preferred embodiment of the invention: Figure 1 is a side elevation of a separating case embodying my invention, showing in dotted lines the position of the slidable receptacles, and one of said receptacles partly removed; Fig. 2 is a front perspective of one of said receptacles removed from the case; Fig. 3 is a side elevation of a receptacle removed from the case; Fig. 4 is a top view of the same; and Fig. 5 is a rear perspective of one of the receptacles.

Referring to the numerals on the drawings, 1 indicates a separating table such as is in common use, having a railed top whereon the mail matter to be sorted is first placed.

2 indicates a pigeon-holed case, divided by partitions 3 which slant downwardly from the front of the case, into a series of spaces adapted to contain the receptacles presently to be mentioned. I have shown in Fig. 1 a series of three such spaces from top to bottom of the case, but it is to be understood that there may be a plurality of such vertical series arranged side by side along the length of the table, this involving simply the use of properly positioned vertical partitions.

—4 indicates the receptacles intended to be used in connection with my invention, comprising a box open at the top and one end, and adapted to slidably fit within the space defined between the partitions constituting a pigeon hole. As shown, the open end of the receptacle is adjacent to the inner face of the pigeon-hole case, and when the receptacle is in position its rear wall forms a part of the rear of the case, the floor of the receptacle slanting downwardly from the front of the case in conformity with the slant of the partitions 3. The rear or closed end of the receptacle is preferably provided with a screen 5, to provide visual access to the interior of the receptacle when it is in place in the case. There is also provided a handle 6 for manipulation of the receptacle, and a spring-latch 8 which takes into a notch in the partition above the receptacle, whereby the receptacle is held removably in position in the case. The receptacle may be of any preferred and suitable material, and is best provided with a brace across its open top, as indicated at 7.

In operation, mail matter is first deposited upon the table 1, and there sorted by a clerk, who throws it into one of the receptacles 4, which are all in their proper places in the pigeon-hole case. Since he must perforce "face" the mail in order to determine into which receptacle it shall go, it follows that the mail matter in each receptacle will be in its "faced" position if the clerk throws it in as he reads it. Now, supposing a receptacle to be full, the carrier having charge of mail deposited in that receptacle has simply to unfasten the latch 8, and withdraw the receptacle with its contained mail matter. If now he removes this to his individual separating table, he may slide the mail matter out of the box onto the table, and it will be properly "faced" and awaiting his further attention, without putting him to the necessity of "facing" it all over again. In the separating cases now in use, where there is simply a door at the rear of each carrier's pigeon-hole, he must take out a hand-full of mail at a time, with the result that it is likely to be very much mixed up when it comes to his table. The object of having the pigeon-holes and their receptacles provided with a slant is to facilitate the dropping of the mail matter as it is deposited toward the rear of the receptacle. These receptacles may be used in connection with the separating tables now in general use, with but few changes to

the latter; and the advantages of this device are too apparent to require further comment.

It is evident, of course, that when not actually in their places in the case, the receptacles are useful in themselves as receptacles, and may be carried about.

What I claim is:—

In a device of the kind described, the combination of a table, a pigeon-hole case thereon 10 open from front to rear, removable receptacles in said pigeon-hole case extending

from front to rear thereof, said receptacles being closed at their back ends and open at the ends adjacent said table, and means for holding said receptacles in place within said 15 pigeon-hole case.

In testimony whereof I affix my signature in presence of two witnesses.

MALIN EWING
